ELEVATOR SYSTEMS

William F. Eames, Westfield, N. J., assignor to Westinghouse Electric Corporation, East Pittsburgh, Pa., a corporation of Pennsylvania

Application August 31, 1954, Serial No. 453,214

19 Claims. (Cl. 187—29)

This invention relates to elevator systems which are automatically modified to provide different modes of operation and it has particular relation to elevator systems having modes of operation which are varied with variations in service demand.

It is well known that the demand for service from an elevator system in the average building varies appreciably throughout the day. For example, during the night in an office building the elevator system usually is required to provide very little service. This period is referred to as an "off-hours" period of operation.

At the start of a business day a substantial demand for service in the up direction from the lower terminal floor occurs. This period is known as an "up-peak" period. A similar period often occurs immediately following the lunch hour.

Immediately prior to the lunch hour and after the close of the business day a peak demand for down service generally is encountered. Such periods are designated "down-peak" periods.

During the remainder of the business day the demand for elevator service in the two directions of travel is substantially balanced. Such periods are known as "off-peak" periods.

In accordance with the invention, an elevator system is provided having a plurality of modes of operation. The mode of operation of the system is varied as a function of the demand for elevator service.

The demand for elevator service may be measured in various ways. For example, the demand for elevator service may be determined by the number of calls for service registered in the elevator system. As a further example, the demand for elevator service may be measured by the rate of movement of loaded elevator cars in a given direction.

The invention contemplates that the response of the elevator system to the demand for elevator service will be modified during certain periods. Such modification conveniently may be introduced by a time switch which operates at predetermined periods of time to effect the desired changes in the response of the elevator system.

In a specific embodiment of an elevator system embodying the invention, the elevator system may be arranged to provide elevator service during the off-peak period which is substantially balanced in the two directions of travel of the elevator cars. When a predetermined demand for elevator service in a given direction is detected, the mode of operation of the elevator system is modified to expedite elevator service in such direction. Thus, if a predetermined demand for elevator service in the upward direction from the lower terminal floor is detected, the mode of operation of the elevator system is modified to expedite travel in the upward direction.

During a period in which intense upward travel is expected, the response of the elevator system to the demand for elevator service may be modified to assist in maintaining the elevator system in the mode of operation which expedites travel in the upward direction. Thus,

2

if an intense up peak is expected between 7:30 A.M. and 8:00 A.M., a time switch may be provided for modifying the response of the elevator system to the demand for elevator service during this period of time.

5 For example, at 7:30, the time switch may operate to render the elevator system responsive to a smaller value of the demand for elevator service in the upward direction to convert the elevator system for up-peak operation. As a further example, the time switch may operate to increase the speed with which the elevator system is conditioned for up-peak operation when a predetermined demand for elevator service in the upward direction is detected and may operate to retard the return of the elevator system to balanced operation when the demand for elevator service in the upward direction decreases.

The invention also is applicable to control the response of the elevator system to other demands for elevator systems. Thus, if a substantial demand for elevator service in the down direction is expected between 5:00 P.M.

20 and 5:30 P.M., the system may respond to the demand for elevator service in the down direction to condition the system for down-peak operation. The operation of a time switch at 5:00 P.M. may operate to decrease the magnitude of the demand for down service to which 25 the elevator system responds, to increase the speed with which the system is conditioned for down-peak operation or to retard the return of the elevator system to balanced or off-peak operation.

It is therefore an object of the invention to provide 30 an improved elevator system having plural modes of operation wherein the mode of operation is responsive to the demand for elevator service and wherein such response is varied during certain periods.

It is a further object of the invention to provide an 35 elevator system having plural modes of operation wherein the mode of operation is responsive to the demand for elevator service and wherein the elevator system responds to the demand for elevator service with a time delay which varies during predetermined periods.

40 Other objects of the invention will be apparent from the following description taken in conjunction with the accompanying drawings, in which:

Figure 1 is a schematic view with circuits shown in 45 straight-line form of a portion of an elevator system embodying the invention;

Figs. 2 to 4 are schematic views with circuits shown in straight-line form of further portions of the elevator system illustrated in Fig. 1; and

Figs. 1A to 4A, respectively, are key representations 50 of relays and switches illustrated in Figs. 1 to 4. If Figs. 1A to 4A are horizontally aligned respectively with Figs. 1 to 4, it will be found that corresponding contacts and coils of relays and switches shown in the horizontally-aligned figures are substantially in horizontal alignment.

55 In some cases involving groups of similar relays only representative relays are shown in the key representations.

In order to facilitate the orderly presentation of the invention, a number of conventions have been adopted. Although the invention may be incorporated in an elevator system having any desired number of elevator cars serving a structure having any desired number of floors or landings, it will be assumed that the invention is incorporated in an elevator system having three elevator cars serving a structure having six floors or landings. The 60 elevator cars are designated by the reference supporters A, B and C. Inasmuch as the circuits associated with the three elevator cars are similar, it will suffice to show primarily the circuits associated with the elevator cars A and B. However certain components associated with the elevator car C also will be referred to.

Because of the similarity of the circuits and components associated with the three elevator cars, components as-

sociated with the elevator cars B and C will be identified by the same reference characters employed for the components associated with the elevator car A preceded by the appropriate letter B or C. For example, the resistors R8, BR8 and CR8 are associated respectively with the elevator cars A, B and C. Consequently the discussion will be directed primarily to the elevator car A and its circuits.

Relays and switches employed for the elevator system may have front or make contacts and back or break contacts. Front or make contacts of a relay are closed when the relay is energized and picked up. The contacts are open when the relay is deenergized and dropped out. Back or break contacts of a relay are closed when the relay is deenergized and dropped out. The back or break contacts are open when the relay is energized and picked up.

Each set of contacts of a relay or switch is designated by the reference characters employed for the relay or switch followed by a suitable numeral specific to the set of contacts. For example, the reference characters U1 and U3 designate the first and third sets of contacts respectively associated with the up switch U of the elevator car A. In the drawings all relays are shown deenergized.

In order to further facilitate the presentation of the invention, certain apparatus specific to car A and certain apparatus common to all of the elevator cars are set forth as follows:

Apparatus for car A:

- E—inductor slowdown relay
- F—inductor stopping relay
- V—speed relay
- U—up switch
- M—running relay
- D—down switch
- G—holding relay
- W—up preference relay
- X—down preference relay
- 70T—non-interference relay
- DR—door relay
- HC—high call reversal relay
- 1CR to 6CR—car call registering relays
- T—car call stopping relay
- 78U—call-above relay
- S—floor call stopping relay
- 78—call relay
- O—quota relay
- SE—timed floor call stopping relay
- J—reversal relay

Apparatus common to all cars:

- 1UR to 5UR—up floor call registering relays
- 2DR to 6DR—down floor call registering relays
- HCM—bank high call reversal relay
- DSE—first down service demand relay
- EM—second down service demand relay
- 2CC, 3CC, 4CC, 5CC—down call quota relays
- 1T, 2T, 3T, 4T—timed call relays
- HCR—second car-call quota relay
- HMCR—first car-call quota relay
- 2DRT to 6DRT—floor-call timing relays
- USE—modifying relay
- PU—auxiliary car-call quota relay
- PUA—auxiliary down call quota relay
- PUT—first timing relay
- DOT—second timing relay
- PUTA—third timing relay
- DOTA—fourth timing relay
- CL—timing switch

Figure 1

Fig. 1 shows the elevator cars A and B and certain control circuits associated therewith. The elevator car A will be assumed to be stopped at the second floor of the structure whereas the elevator car B will be assumed to

be stopped at the fifth floor of the structure. With these exceptions, the circuits and mechanisms associated with the two elevator cars are similar and will be understood by reference to those associated with the elevator car A. Circuits for the elevator A are shown in the left-hand column in Fig. 1.

The elevator car A is connected by a rope or cable 10 to a counterweight 11. The rope 10 passes over a sheave 12, which is secured to a shaft 13 for rotation therewith. The shaft 13 is rotated by a motor 14 which may be of any conventional type. For present purposes it will be assumed that the motor 14 is a direct current motor having its armature 14A secured to the shaft 13 and having a field winding 14F which is permanently connected across two direct-current buses L1 and L2 which supply direct current energy for the control circuits.

The elevator car A has therein a plurality of normally-open car-call push buttons 1c to 6c which are actuated for the purpose of registering calls respectively for the first to sixth floors as desired by passengers entering the elevator car.

To permit registration of calls for service by prospective passengers located at the various floors served by the elevator cars, push button stations are located at such floors. Such a station is shown in Fig. 1 for the third floor. It includes a normally-open up floor call push button 3U which is pressed by a prospective passenger desiring elevator service in the up direction. A similar push button 3D is located at each floor from which service in the up direction may be desired. The station also includes a normally-open push button 3D which is pressed by a prospective passenger desiring elevator service in the down direction. A similar push button is located at each floor from which elevator service in the down direction may be desired. The numeral of the reference characters (as 3D or 3U) indicates the floor at which the push button is located.

The elevator car A also has mounted thereon a slowdown inductor relay E and a stopping inductor F which may be of conventional construction. The slowdown relay E has two sets of break contacts E1 and E2 associated therewith. The relay has a normally incomplete magnetic circuit and initial energization of the winding 45 of the relay alone does not initially open the associated contacts. However, if the slowdown relay E reaches an inductor plate UEP located in the hoistway of the elevator car while the winding of the relay is energized, the contacts E1 open. The inductor relay may be of the type which when it opens the contacts maintains the contacts open until the relay winding is deenergized even though the relay passes beyond the inductor plate. In Fig. 1 the inductor plate UEP is assumed to be mounted in the hoistway to be reached by the slowdown relay E 55 as the elevator car A nears the third floor. If the elevator car A is to stop at the third floor, the winding of the relay E is energized and when the relay reaches the inductor plate UEP for the third floor, the contacts E1 open to initiate a slowdown operation for the elevator car. It will be understood that a similar inductor plate is similarly associated with each of the floors at which the elevator car A may stop during up travel thereof.

During down travel of the elevator car A, the inductor relay E cooperates with down inductor plates DEP to 65 initiate a slowdown of the elevator car as it approaches a floor at which the elevator car is intended to stop. For example, if the elevator car is to stop during down travel at the third floor, the winding of the inductor relay E is energized as the elevator car nears the third floor. When the inductor relay reaches the down inductor plate DEP for the third floor, the contacts E2 open to initiate a slowdown operation of the elevator car. It will be understood that a similar inductor plate DEP is provided for each of the floors at which the elevator car A 70 is to stop during down travel thereof.

The stopping relay F similarly cooperates with inductor plates UFP and DFP for the purpose of bringing the elevator car to a stop as it reaches a floor at which it is to stop. Thus, if the elevator car A during up travel is to stop at the third floor, the winding of the stopping relay F is energized and as the inductor relay of stopping relay F reaches the stopping inductor plate UFP for the third floor, the contacts F1 open. These contacts in opening result in stopping of the elevator car at the third floor. A similar inductor plate is provided at each of the floors for which the elevator car A is to stop during up travel thereof.

If the elevator car A is to stop at the third floor during down travel thereof the winding of the stopping relay is energized and as the relay reaches the inductor plate DFP for the third floor, the contacts F2 open to produce a stopping operation of the elevator car at the third floor. It will be understood that a similar inductor plate is provided for each of the floors at which the elevator car A is to stop during down travel thereof.

Because of the large number of control circuits required, it is conventional practice to provide each elevator car with a floor selector 16. This selector includes a plurality of rows of contact segments mounted on the insulating panel 16A. Only two rows of contact segments a1 to a5 and d1 to d5 are illustrated in Fig. 1. These contact segments are successively engaged during travel of the elevator car respectively by brushes aa and dd for the purpose of controlling the energizations of certain circuits. For example, if the elevator car A during down travel is to stop at the third floor in response to a car call, the brush aa engages the contact a3 shortly before the elevator car A reaches the third floor, to initiate a stopping operation thereof.

The brushes aa and dd are mounted on a brush carriage 16C which is mounted for movement in accordance with movement of the elevator car, but at a greatly reduced rate. In the embodiment of Fig. 1, it is assumed that the carriage 16C has threaded engagement with a screw 16S which is coupled to the shaft 13 through suitable gearing for rotation in accordance with movement of the elevator A. Consequently, as the elevator car A moves, the brushes mounted on the carriage 16C permit the energization of appropriate circuits at various points of travel of the elevator car.

Although the driving motor 14 may be energized in various ways, it will be assumed that the control of this motor is of the type commonly referred to as a variable voltage control. In such a control, a direct current generator 17 has its armature 17A connected in a loop with the armature 14A of the motor. A series field winding 17S for the generator also may be included in this loop. The generator has a main field winding 17F which is connected for energization from the buses L1 and L2 through a reversing switch. This reversing switch includes contacts U2 and U3 of an up switch. When these contacts are closed, the field winding is energized with proper polarity for up travel of the elevator car. On the other hand, when contacts D2 and D3 of a down switch are closed, the field winding is energized with proper polarity for down travel of the elevator car. The energization of the field windings is completed through a resistor R1 for slow speed operation of the elevator car or through make contacts V1 of a speed relay for full speed operation of the elevator car.

The elevator car A is provided with a conventional spring-applied electromagnetically-released brake. This brake includes a brake drum 18D which is secured to the shaft 13 for rotation therewith. A brake shoe 18C normally is biased against the brake drum by means of a spring (not shown). The brake is released upon energization of a brake coil 18B which cooperates with a magnetic armature 18A secured to the shoe 18C. The coil 18B is connected to the buses L1 and L2 for energization either through make contacts U1 or through

make contacts D1 of the up switch U or the down switch D.

The speed relay V is connected for energization from the buses L1 and L2 through either of two paths. One of these paths includes make contacts U4 of the up switch, a limit switch 19 and the break contacts E1 of the slowdown relay. The limit switch 19 is a cam-operated normally-closed switch which is opened as the elevator car nears its upper limit of travel.

5 The remaining path of energization comprises the make contacts D4 of the down switch, a limit switch 20 and the break contact E2 of the slowdown relay. The limit switch 20 may be cam operated. It is normally closed and is opened as the elevator car A nears its lower limit of travel.

10 As long as the elevator car A is running, the running relay M is energized. This relay can be energized only as long as the make contacts DR1 of a door relay DR are closed. These contacts are closed only as long as all of the 15 hoistway doors and car doors for the car A are closed. Such safety provisions are well known in the art.

15 The running relay M initially can be energized only if the break contacts 78-1 are closed to indicate that a call for service has been registered and if the break contacts 25 70T1 are closed to indicate that sufficient time has elapsed since the last stop of elevator car A to permit discharge or entry of passengers.

20 Assuming that the foregoing contacts associated with the running relay M are closed, the relay may be energized 30 initially through either of two paths. One of these paths is as follows:

L1, 70T1, 78-1, W1, F1, 21, U, M, DR1, L2

35 Since the up switch U is energized through this path, it follows that the elevator car will be conditioned for up travel. The limit switch 21 is a normally-closed mechanically-operated switch which is opened as the elevator car A nears its upper limit of travel. When energized, the up switch U closes its make contacts U5 to establish a 40 holding circuit around the contacts 70T1, 78-1 and W1.

The second path for initially energizing the running relay M may be traced as follows:

L1, 70T1, 78-1, X1, F2, 22, D, M, DR1, L2

45 Since the down switch D now is energized, it follows that the elevator car A is conditioned for down travel. The limit switch 22 is a mechanically-operated normally-closed switch which is opened as the elevator car A nears its lower limit of travel. When it picks up, the down switch 50 D closes its make contacts D5 to establish a holding circuit around the contacts 70T1, 78-1 and X1.

55 If the elevator car A is to be operated by a car attendant the contacts 78-1 and 70T1 may be replaced by a manually-operated switch which is closed by the car attendant when the car is to be moved from a floor at which it is stopped. However in a preferred embodiment of the invention the automatically-operated contacts 78-1 and 70T1 are employed.

60 The slowdown relay E, the inductor relay F, and a holding relay G are energized in parallel from the buses L1 and L2 through make contacts M1 of the running relay M. To complete an energizing circuit for these relays E, F and G, one of the following conditions must be present: First, the make contacts T1 are closed to indicate that a

65 car call is registered for a floor which the elevator car A is approaching. Second, the contacts J1 are closed to indicate that the elevator car A is conditioned to reverse at the next floor reached by the elevator car. Third, the make contacts S1 are closed to indicate that the elevator car A is conditioned to stop at a floor in answer to a registered floor call for such floor. Fourth, the contacts SE1 are closed to indicate that the elevator car A is approaching a floor for which a priority floor call has been registered for a long period of time.

70 When the holding relay G is energized, it closes its

make contacts **G1** to establish with the make contact **M1** a holding circuit for the inductor relays **E** and **F**.

The direction of travel of the elevator car **A** is determined initially by an up preference relay **W** and a down preference relay **X**. For the up preference relay **W** to be energized, the break contacts **D6** must be closed (i. e. the down switch **D** is energized). The break contacts **X2** must be closed (i. e. the down preference relay **X** is de-energized). The limit switch **23** also must be closed. This switch is normally closed and is opened as the elevator car **A** reaches its upper limit of travel, in this case, the sixth floor.

Energization of the up preference relay **W** also requires closure of at least one of two sets of contacts. These include the break contacts **J2** which are closed when the elevator car **A** is not conditioned to reverse at the nearest floor in its direction of travel. Make contacts **M2** are closed as long as the elevator car **A** is running.

The down preference relay **X** is energized if the break contacts **U6** are closed (i. e. the up switch **U** is de-energized), the break contacts **W2** are closed (i. e. the up preference relay is deenergized) and the limit switch **24** is closed. This limit switch is normally closed and is opened as the elevator car **A** reaches the lower terminal floor.

As long as the elevator car **A** is running, the make contacts **M3** are closed to energize the non-interference relay **70T**. When the elevator car **A** stops, the contacts **M3** open to deenergize the relay. However, the relay **70T** has a substantial delay in dropout. This delay may be provided in any suitable manner as by connecting a resistor **R2** across the relay coil. The time delay in dropout is selected to be sufficient to permit discharge of passengers from the elevator car **A** or entry of passengers into the elevator car **A** after each stop.

It will be recalled that door relay **DR** is connected across the buses **L1** and **L2** through contacts operated by each door associated with the elevator car **A**. If any of the doors is open, the contacts associated therewith are also open to prevent energization of the door relay **DR**.

Energization of the high call reversal relay **J** prepares the elevator car **A** to reverse during up travel at the nearest floor. The high call reversal relay **J** may be energized if the elevator car **A** is conditioned for up travel (break contacts **X3** are closed) and if certain other conditions are satisfied.

Thus, if at least a predetermined number of priority down floor calls are registered, make contacts **1T1** are closed. If at least a predetermined number of down floor calls are registered, make contacts **2CC1** are closed, or if at least a predetermined number of car calls are registered for the system, the make contacts **MHCR1** are closed. If in addition to one of these closures the make contacts **78U1** are closed to indicate no higher calls remain to be answered (in some cases no higher car calls), the energizing circuit for the reversal relay **J** may be completed.

Figure 2

Figure 2 shows the call registration circuits for the elevator cars. Car call registration circuits are illustrated for the elevator cars **A** and **B** in the upper part of this figure.

It will be recalled that the elevator car **A** is provided with a plurality of push buttons **1c** to **6c** for the purpose of registering car calls. Inasmuch as car call push buttons and associated circuits for the intermediate floors are similar, they are not illustrated in Fig. 2 for the third and fourth floors. Each of these push buttons has associated therewith a car call registering relay **1CR** to **6CR** respectively. In this group only representative relays **6CR**, **2CR** and **1CR** are shown in Figs. 2A and 3A. The push buttons and call registration relays cooperate with four rows of contact segments located on the floor selector for the elevator car **A**. The contact segments **a1** to **a5** cooperate with the brush **aa** for the purpose of initiating a stopping operation of the elevator car during

down travel of the elevator car respectively at the first to fifth floors. The contact segments **b2** to **b6** cooperate with a brush **bb** for the purpose of initiating a stopping operation of the elevator car during up travel of the elevator car respectively at the second to sixth floors. A brush **cc** cooperates with a row of contact segments **c2** to **c6** and a brush **dd** cooperates with a row of contact segments **d1** to **d5** for the purpose of cancelling registered car calls as they are answered respectively during down travel and up travel of the elevator car. It will be understood that for each contact segment, the numeral of the reference character designates the floor with which the contact segment is associated. Thus, the reference character **a1** designates the contact segment for the first floor in the **a** row.

By reference to Fig. 2, it will be observed that when the car call push button **5c** is pressed the car call registering relay **5CR** is connected therethrough across the buses **L1** and **L2**. This relay closes its make contacts **5CR1** to establish a holding circuit around the push button. The contact segments **a5** and **b5** are connected through this set of contacts to the bus **L1**.

If the elevator car **A** is set for down travel, the make contacts **X4** are closed. And if the elevator car is approaching the fifth floor, the make contacts **M4** of the running relay also are closed. Consequently, as the elevator car nears the fifth floor, the brush **aa** engages the contact segment **a5** to complete the following circuit for the car call stopping relay **T**:

L1, 5CR1, a5, aa, X4, T, M4, L2

The energization of the relay **T** initiates a stopping operation of the elevator car **A** at the fifth floor.

As the elevator car **A** continues its approach toward the fifth floor, the contact segment **c5** is engaged by the brush **cc**. As the elevator car comes to a stop, the break contacts **M5** of the running relay close to complete the following cancelling circuit:

L1, 5CR1, 5CRN, c5, cc, X5, M5, L2

40 The operating coil of the registering relay **5CR** and the cancelling coil **5CRN** are wound in opposition on a common core. Consequently, energization of the cancelling coil **5CRN** cancels the effect of the operating coil and resets the registering relay **5CR**. Preferably, as the elevator car stops at the fifth floor, the brush **aa** passes slightly below the associated contact segment **a5**, however, the brush **cc** remains in engagement with the associated contact segment **c5** as long as the elevator car **A** remains at the floor.

45 Next it will be assumed that the same call is registered for the fifth floor as the elevator car **A** travels up towards the fifth floor. Under these circumstances, the make contacts **W3** and **W4** of the up preference relay are closed. As the elevator car **A** nears the fifth floor, the brush **bb** engages the contact segment **b5** to complete the following circuit:

L1, 5CR1, b5, bb, W3, T, M4, L2

60 The energization of the car call stopping relay **T** results in the initiation of a stopping operation for the fifth floor.

As the elevator car **A** continues to approach the fifth floor, the brush **dd** engages the contact segment **d5** to complete the following circuit:

L1, 5CR1, 5CRN, d5, dd, W4, M5, L2

65 The energization of the cancelling coil **5CRN** resets the call registering relay **5CR**. During the stopping operation, the brush **bb** preferably passes slightly above the associated contact segment **b5** whereas the brush **dd** remains in engagement with the associated contact segment **d5** as long as the elevator car **A** is at the fifth floor.

The car call registering circuits for all of the intermediate floors are similar to those described for the fifth floor. For this reason and to conserve space, the inter-

mediate floor circuits are illustrated in Fig. 2 only for the second and fifth floors.

The car call registering circuits for the upper terminal (sixth floor) may be similar to those employed for the intermediate floors. However, since the elevator car A stops at the sixth floor only during up travel, contact segments for the sixth floor need not be provided in the *a* and *d* rows. By reference to Fig. 2 it will be noted that only contact segments *b*6 and *c*6 are provided for the sixth floor.

The car call registering circuits for the lower terminal or first floor may be similar to those provided for the intermediate floors. Since the elevator car stops at the first floor only during down travel, contact segments for the first floor need not be provided in the *b* and *c* rows. For this reason, in the car call registering circuits only contact segments *a*1 and *d*1 are illustrated for the first floor.

The central part of Fig. 2 illustrates up floor call registering circuits. These circuits are operated by means of normally-open push buttons 1U to 5U common to all of the elevator cars which are located respectively at the first to fifth floors. Inasmuch as the push buttons and associated circuits for the intermediate floors are similar, they are not shown for the third and fourth floors. The push buttons have associated therewith up floor call registering relays 1UR to 5UR and cancelling coils 1URN to 5URN in a manner which will be clear from the discussion of the call registering relays and cancelling coils associated with the car call push buttons.

The up floor call registering relays 1UR to 5UR and their cancelling coils are associated with contact segments for each of the elevator cars in the bank. For example, a row of contact segments *e*1 to *e*6, respectively for the first to sixth floors, is provided for the elevator car A and cooperate with a brush *ee*. A brush *ff* cooperates with a row of contact segments *f*1 to *f*5, respectively for the first to fifth floors for the elevator car A.

Let it be assumed that while the elevator car A is traveling up a prospective passenger waiting on the fifth floor presses the up floor call push button 5U to energize the up floor call registering relay 5UR. This relay closes its make contact 5UR1 to establish a holding circuit around the push button.

Since the elevator car is assumed to be travelling up, the make contacts W5 of the up preference relay W are closed. It will be assumed further that the break contacts MHCR3 (Fig. 2) of the first car-call quota relay MHCR are closed. (Although the elevator car B may employ similar contacts of the relay MHCR, in the embodiment illustrated the elevator car B does not employ such contacts but instead employs in the corresponding circuit break contacts HCR1 of a second car-call quota relay HCR. In addition, the elevator car B circuit includes break contacts 3CC1 of a down call quota relay 3CC and break contacts 2T1 of a timed call relay 2T.) It is assumed that break contacts EM1 of the second down service demand relay EM are closed. As the elevator car A nears the fifth floor, the brush *ee* engages the contact segment *e*5 to complete the following circuit:

L1, 5UR1, *e*5, *ee*, W5, MHCR3, S, EM1, L2

The energization of the floor call stopping relay S initiates the stop at the fifth floor. In response to movement of the car towards the fifth floor, the brush *ff* engages its contact segment *f*5. As slow down of the elevator car is initiated, the break contacts V6 close to complete the following cancelling circuit:

L1, 5UR1, 5URN, *f*5, *ff*, W6, V2, L2

This resets the up floor car registering relay 5UR. As the elevator car A comes to a stop, the brush *ee* preferably passes slightly above the contact segment *e*5. However, the brush *ff* remains in engagement with the contact segment *f*5 as long as the elevator car A remains at the fifth floor. By inspection of Fig. 2, it will be observed

that the contact segment *e*5 is connected to the corresponding contact segments for the other elevator cars in the bank (such as contact segment B*e*5 for the elevator car B). Similarly, the contact segment *f*5 is connected to corresponding contact segments (such as the contact segment B*f*5) for the remaining cars of the bank. Consequently, operation of the push button 5U is effective to stop the first up traveling elevator car which reaches the fifth floor and which is conditioned to accept the call at the fifth floor.

The up floor call registering circuits for all of the intermediate floors are similar. Consequently, such circuits are illustrated in Fig. 2 only for the second and fifth floors.

During up travel, the elevator cars also stop at the sixth floor if they reach such floor. For this reason, a single contact segment *e*6 suffices for the sixth floor and is permanently connected to the bus L1. Since the elevator car A does not stop during up travel at the lower terminal or first floor, a contact segment in the *e* row is not required. With this exception, the call registering circuits for the first floor are similar to those described for the fifth floor.

The lower part of Fig. 2 illustrates the down floor call registering circuit for the elevator cars. Down floor calls are registered by operation of normally-open push buttons 2D to 6D for the second to sixth floors, respectively which have associated therewith down floor call registering relays 2DR to 6DR and cancelling coils 2DRN to 6DRN. Each push button cooperates with its call registering relay and its cancelling coil in the manner discussed with reference to the up floor call push buttons. Only relays 2DR, 3DR and 6DR in this group are shown in Figs. 2A, 3A and 4A.

For the elevator car A, a row of contact segments *g*1 to *g*5 cooperates with a brush *gg* and a row of contact segments *h*2 to *h*6 cooperates with a brush *hh*. Let it be assumed that the elevator car A while traveling down is approaching the fifth floor at which a down floor call has been registered by operation of the push button 5D. Such operation results in energization of the down floor call registering relay 5DR to close the make contacts 5DR1. Since the elevator car is traveling down, the make contacts X6 and X7 are closed. It will be assumed that break contacts HCR3 and EM1 are closed.

As the elevator car A nears the fifth floor, the brush *gg* engages the contact segment *g*5 to complete the following circuit:

L1, 5DR1, *g*5, *gg*, HCR3, X6, S, EM1, L2

The energization of the floor call stop relay S initiates a stopping operation of the elevator car A at the fifth floor. As the elevator car continues its approach, a brush *hh* engages the contact segment *h*5. The initiation of slow down of the elevator car A results in closure of the break contacts V2 to complete the following cancelling circuit:

L1, 5DR1, 5DRN, *h*5, *hh*, X7, V2, L2

The energization of the cancelling coil resets the call registering relay 5DR. Preferably, as the elevator car A comes to a stop, the brush *gg* passes slightly below the associated contact segment *g*5, but the brush *hh* remains in engagement with the associated contact segment *h*5.

The contact segment *g*5 is connected to corresponding contact segments (such as the contact segment B*g*5) of the remaining cars. Similarly, the contact segment *h*5 is connected to the corresponding contact segments (such as the contact segment B*h*5) for the remaining cars. Consequently, the first elevator car to approach the fifth floor while traveling down will answer a call registered by the call registering relay 5DR.

The down floor call registering circuits for all of the intermediate floors are similar and may be traced readily in Fig. 2. The down floor call registering relays for the upper terminal or sixth floor also may be similar. How-

ever, since the elevator car A does not stop at the sixth floor during down travel, the contact segment in the g row may be omitted for the sixth floor. Since the elevator car A always stops at the lower terminal floor, a single first floor contact segment **g1** may be provided for the elevator car A and this contact segment may be permanently connected to the bus **L1**.

A normally-open mechanical switch **28** may be cam-operated to closed position as the elevator car A approaches the upper and lower terminal floors to shunt the contacts **EM1**.

In Fig. 3, a call circuit **30** for car A is provided which has two functions. This circuit energizes a call relay **78** when no call is registered in the elevator by the car call push buttons for the elevator car A or by any floor call push button. In addition, the call circuit **30** energizes the call above relay **78U** as the elevator car during up travel nears the highest floor for which a down floor call on a car call is registered provided no up floor call is registered for such floor or a higher floor.

The call-above circuit **30** includes break contacts for all of the floor call registering relays and for all of the elevator A car call registering relays arranged in the order of the floors. This circuit may be traced as follows:

L1, 6CR2, 6DR2, 5UR2, 5CR2, 5DR2, 4UR2, 4CR2, 4DR2, 3UR2, 3CR2, 3DR2, 2UR2, 2DR2, 2CR2, 1CR2, 1UR2, 78, L2

By inspection of this circuit, it will be observed that as long as a call is registered by the car call push buttons for the elevator car A or by the floor call push buttons the relay **78** is deenergized.

The call circuit **30** has associated therewith a row of contact segments **k1** to **k5** which are engaged successively by the brush **kk** as the elevator car A moves. The contact segments are so located relative to the call circuit **30** that each contact segment is placed below all break contacts of the call circuit which require travel of the elevator car A above such contact segments. Thus, the contact segment **k5** is connected to the call circuit between the contacts **5UR2** and **5CR2**. The contact segment **k4** is connected between the contacts **4UR2** and **4CR2**. The location of the remaining contact segments similarly may be ascertained by reference to Fig. 3. It will be noted that the relay **78U** is connected between the brush **kk** and the bus **L2** through make contacts **W7** of the up preference relay **W**.

In certain cases, it is desirable to prevent registered calls from affecting the call circuit **30**. For example, it may be desirable under some conditions to prevent registered floor calls from affecting the operation of the relay **78U** and **78**. To this end, make contacts of the first car-call quota relay **MHCR** are provided for the purpose of shunting the break contacts of the floor call relays. When the relay **MHCR** is energized, the contacts **MHCR4** to **MHCR8** close to shunt contacts **5UR2** to **2UR2** and **6DR2** to **2DR2**.

Although contacts of the relay **MHCR** similarly may be associated with the call circuit **B30** for the elevator car B, in a preferred embodiment of the invention a separate relay **HCR** has make contacts **HCR4** to **HCR8** associated with the call circuit **B30** to shunt contacts **5UR3** to **2UR3** and **6DR3** to **2DR3**, as clearly shown in Fig. 3.

Make contacts **EM3** to **EM6** and **USE1** to **USE4** are arranged to shunt contacts of the up floor call registering relays in the call circuits **30** and **B30** for floors above the first floor.

The down call quota relays **2CC** to **5CC** indicate the presence of predetermined service demands. As shown in Fig. 3, the quota relays and a relay **PUA** preferably are energized in accordance with the number of registered down floor calls. The energization of the relays is dependent on the condition of a parallel circuit having five parallel arms. Each arm contains a suitable re-

sistor and a set of make contacts of a separate one of the down floor call registering relays. The resistors are so proportioned that a predetermined number of down floor calls must be registered before the relays will pick up. **5** A switch **SW6** controls in part the energization of the relay **2CC**. For the present it will be assumed that the switch **SW6** connects the relay **2CC** in series with the relays **3CC** to **5CC**.

The number of calls to which the down call quota relays respond depends on the number of floors of the elevator system, the number of elevator cars and other factors of the particular installation. For present purposes it will suffice to assume that the relays **2CC**, **3CC**, **4CC** and **5CC** pick up respectively in response to registration of two, three, four and five down floor calls. A resistor **R24** may be provided for controlling the sensitivity of the relay **5CC**.

The circuits of Fig. 3 which have thus far been described specifically are for the purpose of providing various modes of operation which are selected at all times in accordance with the demand for elevator service. As previously pointed out, it is desirable in many elevator systems to modify the response of the elevator system to the demand for elevator service during certain periods. **25** Such variation in response is provided by the circuits in Fig. 3, which now will be described.

Let it be assumed that the switch **SW6** is operated to its lower position as illustrated in Fig. 3 wherein a shunt is established across the poles or blades of the switch. **30** Under such circumstances, the relays **3CC**, **4CC**, **5CC** are connected for energization in the manner previously discussed. It will be noted that the auxiliary down call quota relay **PUA** also is connected in series with the relays **3CC** to **5CC**. This relay may be designed to pick up when energized in response to registration of a predetermined number of down floor calls, such as two calls.

The relay **PUA** cooperates with circuits which are placed in effective condition by closure of a switch **SW1**. At the same time, the switch **SW5** is closed to connect the relay **2CC** for energization through the break contacts **PUTA1** and the switch **SW1**.

The closure of the switch **SW1** energizes the third timing relay **PUTA** through the break contacts **PUTA1**. The relay **PUTA** has a time delay in dropout which is controlled by the effective resistance of a resistor **R20**. A decrease in effective resistance increases the time delay. The effective value of this resistor may be reduced by closure of the contacts **CL2** of a time switch. For present purposes, it will be assumed that these contacts open during periods of the day when intense demand for down peak service is anticipated.

The relay **PUA** has make contacts **PUTA2** which control the energization through the switch **SW1** of the fourth timing relay **DOTA**. This timing relay has a time delay in dropout which is determined by the effective resistance of a resistor **R21**. The effective resistance of this resistor is reduced by closure of the contacts **CL1** of the time switch. It will be assumed that the contacts **CL1** are closed only when the contacts **CL2** are open.

When the relay **2CC** picks up, it closes make contacts **2CC4** which partially establish a self-holding circuit for the relay. The holding circuit also includes make contacts **DOTA1** of the fourth timing relay **DOTA**. It will be understood that the relay **2CC** also operates its previously discussed contacts.

Figure 4

The timed call relays **1T**, **2T**, **3T** and **4T** compute the number of registered down floor calls which have been registered for more than a predetermined time. To this end the relays are energized through a parallel circuit having five parallel arms. Each of the arms includes a set of break contacts **2DRT1** to **6DRT1**. These contacts close respectively when down floor calls have been registered respectively at the second to sixth floors for more than a predetermined time.

The resistors RT1 to RT5 in the parallel circuit and the timed call relays 1T to 4T are so selected that each of the time call relays picks up in response to registration of at least a predetermined time. For present purposes, it will suffice to assume that the relay 1T picks up if one or more down floor calls has been registered for more than the predetermined time. The relay 2T picks up only if it is energized through two or more of the resistors RT1 to RT5 to indicate that two or more timed out or priority down floor calls are registered. In an analogous manner the relays 3T and 4T pick up in response to the presence of at least respectively three and four timed out or priority down floor calls.

The down call quota relays 2CC to 5CC (Fig. 3) and the timed call relays 1T to 4T (Fig. 4) are employed for computing the demand for elevator service in the down direction and for controlling the operation of the elevator system in accordance with such demand. It will be recalled that closure of the make contacts 1T1 or 2CC1 (Fig. 1) prepares the reversal relay J for energization as the elevator car A when traveling up approaches the farthest floor for which a call is registered provided such call is not an up floor call. In Fig. 2 opening of either the break contacts 2T1 or the break contacts 3CC1 prevents response of the elevator car B to up floor calls. In Fig. 3 closure of the make contacts 2T2 or 3CC2 energizes the modifying relay USE.

The pickup of the down call quota relay 4CC or of the timed call relay 3T indicates a still further increase in the demand for down service. The pickup of either of these relays is accompanied by closure of the make contacts 4CC1 or 3T1 to energize the first down service relay DSE (Fig. 3). The energization of this relay may increase the capacity of the elevator system to handle down traffic in a known manner, as by dividing the floors into zones or groups each served by a separate group of elevator cars.

A still further increase in the demand for down service is accompanied by pickup of the down call quota relay 5CC or of the timed call relay 4T. Pickup of either of these relays is accompanied by closure of the make contacts 5CC1 or 4T1 to energize a second down service demand relay EM. Pickup of this relay results in opening of the break contacts EM1 (Fig. 2) and similar contacts for the other elevator cars of the system to prevent energization of the floor call stopping relays. As will be pointed out in the discussion of Fig. 4, during the energization of the second down service demand relay EM the elevator cars can respond to down floor calls only if such calls have been registered for more than a predetermined time.

The performance of the elevator system also is controlled by the first car call quota relay MHCR (Fig. 4) and the second car call quota relay HCR. These relays are connected in series with each other, when the switch SW3 is in the position illustrated, and in series with break contacts 2CC3 and 1T3 and a relay PU for energization through a parallel circuit containing a plurality of arms. Each of the arms includes a set of make contacts of a separate one of the car call registering relays and a resistor. In order to conserve space only two arms are illustrated for each of the elevator cars A, B and C. Thus for the elevator car A one of the arms contains break contacts 1CR3 and a resistor R8. A second arm contains break contacts 6CR3 and a resistor R13. It will be understood that a similar arm is provided for each of the car call registering relays associated with each of the elevator cars.

The first car call quota relay MHCR is designed to pick up when energized through at least a predetermined number of the parallel arms of its energizing circuit. For present purposes it will be assumed that this relay is picked up only if energized through at least three arms of the parallel circuit.

The second car call quota relay HCR is designed to

pick up when energized through a larger number of arms of the parallel circuit. For the purpose of discussion it will be assumed that this relay is designed to pick up only if energized by at least six arms of the parallel circuit.

5 The pickup point of either of the relays may be adjusted in any suitable manner as by connecting an adjustable resistor thereacross. As a specific example, an adjustable resistor RH is illustrated in parallel with the second car call quota relay HCR.

10 If desired, each of the parallel arms through which the relays HCR and MHCR are energized may include make contacts of the up preference relay for the associated elevator car. If such an expedient is adopted, the relays are energized in accordance with the number of car calls

15 registered by passengers desiring to travel in the up direction. However, for present purposes it will be assumed that such contacts of up preference relays are not employed.

A modified operation during up-peak periods may be 20 obtained by operating the switch SW3 to its upward position, as viewed in Fig. 4, wherein the poles or blades of the switch are shunted. In addition, switch SW4 is closed to connect the relay MHCR for energization through the break contacts PUT1, IT3 and 2CC3.

25 The relay PU is connected in series with the relay HCR and is designed to pick up when energized through a predetermined number of arms of the associated parallel circuit. For present purposes, it will be assumed that this relay picks up when energized through three or more of

30 the arms. If the switch SW2 is closed, the first timing relay PUT is energized through the break contacts PU1, IT3 and 2CC3. This relay has a time delay in dropout which is determined by the effective value of the resistor R22. The resistor R22 has its resistance reduced by

35 closure of the contacts CL4 of a time switch. These contacts will be assumed to be open during periods when an intense demand for elevator service in the up direction from the lower terminal floor is anticipated.

Make contacts PU2 of the auxiliary car call quota 40 relay, together with the break contacts IT3 and 2CC3, control the energization of the second timing relay DOT. This relay has a time delay in dropout determined by the effective value of the resistor R23. The effective value of resistance of this resistor is increased by opening of the contacts CL5 of the time switch which are assumed to be closed when the contacts CL4 are open. Pickup of the relay DOT closes make contacts DOT1 to complete with the make contacts MHCR9 a holding circuit around the contacts PUT1.

50 The floor call timing relays 2DRT to 6DRT are employed for the purpose of measuring the duration of registration of each down floor call. For example, the floor call timing relay 2DRT for the second floor is connected across the buses L1 and L2 through break contacts 2DR5 of the down floor call registering relay 2DR for the second floor. When a down floor call is registered for the second floor the break contacts 2DR open to deenergize the floor call timing relay 2DRT. This relay has a substantial time delay in dropout. This time delay may be provided in any suitable manner. For purposes of illustration it will be assumed that a resistor 2R7 is connected across the relay for the purpose of delaying its dropout. For present purposes it will be assumed that the delay in dropout of the relay is of the order of 40 seconds. Each of the remaining floor call timing relays 3DRT to 6DRT 55 similarly is associated with break contacts of the down floor call registering relay for the associated floor.

60 It will be recalled that break contacts 2DRT1 to 6DRT1 of the floor call timing relays control the energization of the timed call relays 1T to 4T (Fig. 3). In addition, the floor call timing relays have break contacts 2DRT2 to 5DRT2 (Fig. 4) which are employed for the purpose of controlling the energization of a timed floor call stopping relay SE for the elevator car A and similar relays for the remainder of the elevator cars employed in the system.

70

By inspection of Fig. 4 it will be noted that the elevator car A is provided with a row of contact segments *n*2 to *n*5 which may be mounted on the floor selector for the elevator car A. Each of these contact segments is connected to a similar contact segment for each remaining elevator car of the system. A brush *nn* is associated with the row of contact segments for the elevator car A. As the elevator car A moves from the sixth floor to the lower terminal floor, the brush *nn* successively engages the contact segment *n*5 to *n*2 as the elevator car approaches respectively the fifth to second floors.

Each of the contact segments such as *n*2 is connected to a conductor LC through break contacts such as 2DRT2 of the floor call timing relay associated with the same floor. The brush *nn* is connected to the bus DC—through the timed floor call stopping relay SE and make contacts X8 of the down preference relay X. The conductor LC is connected to the bus L1 through make contacts EM11. Consequently, if the contacts EM11 are closed and the elevator car A is traveling in the down direction, the timed floor call stopping relay SE will be energized as the elevator car A approaches each floor for which a down floor call has been registered for more than a predetermined time.

Operation

In order to assure a full understanding of the invention, certain typical operations of the elevator system now will be considered. First, it will be assumed that the elevator cars are parked at the lower terminal floor and that a passenger enters the elevator car A at the lower terminal floor for the purpose of proceeding to the fifth floor.

The doors of the elevator cars may be of the manually-opened, spring-closed type or may be of conventional power-operated design. Upon entering the elevator car A, the passenger presses the car call push button 5c (Fig. 2) to energize the associated car call registering relay 5CR. This relay closes its make contacts 5CR1 to establish a holding circuit around the push button. The relay also opens its break contacts 5CR2 (Fig. 3) to deenergize the relays 78U and 78. Inasmuch as the elevator car A is at the lower terminal floor, it will be understood that the up preference relay W is energized and picked up.

The car call registering relay also closes its make contact 5CR3 (not shown in Fig. 3 but similar to 6CR3). However, it will be recalled that the energization of the relays MHCR and HCR through a single one of the resistors R8 to R13 is insufficient to pick up either relay.

Inasmuch as the relay 78 is now dropped out, the contacts 78-1 (Fig. 1) are closed. It will be assumed also that the elevator car A has remained at the lower terminal floor for a time sufficient to result in closure of the break contacts 70T1. Consequently, upon closure of the doors, the door relay DR closes its make contacts DR1 to complete the following circuit:

L1, 70T1, 78-1, W1, F1, 21, U, M, DR1, L2

Upon energization, the up switch U closes its make contacts U1 to release the elevator brake. Contacts U2 and U3 close to energize the generator field winding 17F with proper polarity for up travel of the elevator car. Contacts U4 close to complete the following energizing circuit for the speed relay V:

L1, U4, 19, E1, V, L2

The speed relay closes its make contacts V1 to shunt the resistor R1 and conditions the elevator car for full speed operation. The speed relay V also opens its break contacts V2 (Fig. 2) without immediate effect on the system operation.

Continuing with the operation of the up switch U, the energized up switch closes its make contacts U5 to establish a holding circuit around the contacts 70T1, 78-1 and W1. Break contacts U6 open to prevent energization therethrough of the down preference relay X.

The elevator car A now accelerates in the up direc-

tion for the purpose of carrying the passenger to the fifth floor.

It will be recalled that the running relay M also was energized. As a result of its energization, the running relay closes its make contacts to prepare the relays G, E and F for subsequent energization. The make contacts M2 close to maintain the energization of the up preference relay despite subsequent opening of the break contacts J2. Make contacts M3 close to energize the non-interference relay 70T. The non-interference relay opens its break contacts 70T1 but such opening has no immediate effect on the operation of the system.

Referring to Fig. 2, the running relay M closes its make contacts M4 and opens its break contacts M5. Such contact operations have no immediate effect on the operation of the system.

As the elevator car nears the fifth floor, the brush *kk* (Fig. 3) engages the contact segment *k*5 which is positioned above the open break contacts 5CR2. Consequently, the call-above relay 78U is energized through the circuit:

L1, 6CR2, 6DR2, 5UR2, *k*5, *kk*, W7, 78U, L2

The relay 78U closes its make contacts 78U (Fig. 1). Under the assumed conditions, the energization of the relay 78U has no immediate effect on the operation of the system.

However, the approach of the elevator car A towards the fifth floor brings the brush *bb* (Fig. 2) into engagement with the contact segment *b*5 to energize the car call stopping relay T through the circuit

L1, 5CR1, B5, *bb*, W3, T, M4, L2

The car call stopping relay closes its make contacts T1 (Fig. 1) to energize through the contact M1 the three relays G, E and F in parallel. The relay G closes its make contacts G1 to establish a holding circuit around the contacts T1.

The energization of the inductor slowdown and stopping relays E and F prepares these relays for subsequent operation. As the elevator car A nears the fifth floor, the inductor slowdown relay E reaches the inductor plate UEP for the fifth floor which completes a magnetic circuit resulting in the opening of the normally-closed contacts E1. Such opening deenergizes the speed relay V. As a result of the deenergization of the speed relay V, make contacts V1 open to introduce the resistor R1 in series with the generator field winding 17F. The resulting decrease in the output of the generator slows the elevator car A to a landing speed. Closing of break contacts V2 (Fig. 2) has no immediate effect on the system.

As the elevator car A slowly approaches the fifth floor, the stopping relay F reaches the inductor plate UFP for the fifth floor. This completes a magnetic circuit which results in opening of the normally-closed contacts F1. In opening the contacts F1 deenergizes the up switch U and the running relay M.

The up switch U now opens its make contacts U1 to apply the elevator brake. Contacts U2 and U3 open to deenergize the generator field winding and the elevator car now stops accurately at the fifth floor. Opening of the make contacts U4 and U5 and closure of the break contacts U6 have no immediate effect on the operation of the system.

The running relay M opens its make contacts M1 to deenergize the relays G, E and F. The relay G opens its make contacts G1. Opening of the make contacts M2 has no immediate effect on the system operation. Make contacts M3 open to deenergize the non-interference relay 70T. This relay now starts to time out. Opening of make contacts M4 (Fig. 2) has no immediate effect on system operation.

Referring to Fig. 2, it should be noted that as the elevator car A continues its approach toward the fifth floor, the brush *dd* engages the contact segment *d*5.

When the running relay drops out to close its break contacts M5, the following cancelling circuit is completed:

L1, 5CR1, 5CRN, d5, dd, W4, M5, L2

Consequently, the car call registering relay 5CR is reset. As the car comes to a stop, the brush *bb* passes slightly above the associated contact segment *b5*.

The resetting of the call registering relay 5CR opens the make contacts 5CR1. In addition, the break contacts 5CR2 (Fig. 3) reclose to complete an energizing circuit for the call relay 78 (Fig. 3). The make contacts 5CR3 open to interrupt the partial energization of the relays MHCR and HCR.

The call relay 78 as a result of its energization opens its break contacts 78-1 (Fig. 1). Consequently, when the non-interference relay 70T times out and recloses its break contacts 70T1, the up switch U and the running relay M can not be energized until a call is registered from one of the floors or in the elevator car A to close the contact 78-1.

Next it will be assumed that as the elevator car A was leaving the first floor in the preceding example, a prospective passenger at the second floor registered an up floor call by operation of the up floor call push button 2U (Fig. 2). Such operation energizes the up floor call registering relay 2UR which closes its contact 2UR1 to establish a holding circuit around the push button. In addition, the registering relay opens its break contacts 2UR2 in the call circuit 30 (Fig. 3) and similar contacts, such as the contact 2UR3, in the call circuits for the remaining elevator cars in the bank. Since the registration of the car call for the fifth floor in the elevator car A has deenergized the relays 78U and 78, opening of the contacts 2UR2 has no effect thereon. However, the opening of the contacts may affect the remaining elevator cars of the system. For example, the opening of the break contacts 2UR3 deenergizes the relay 78 for the car B and permits operation of such elevator car.

As the elevator car A nears the second floor, the brush *ee* engages the contact segment *e2* to establish the circuit:

L1, 2UR1, *e2*, *ee*, W5, MHCR3, S, EM1, L2

The resultant energization of the floor call stopping relay S results in closure of make contacts S1 (Fig. 1) to energize the relays G, E and F. These cooperate to stop the elevator car A at the second floor by a sequence which will be clear from the preceding discussion of the stopping of the elevator car at the fifth floor. As the elevator car stops, the engagement of the brush *ff* with the contact segment *f2* and the closure of the break contacts V2 completes the following cancelling circuit:

L1, 2UR1, 2URN, *f2*, *ff*, W6, V2, L2

This resets the up floor call registering relay 2UR in the manner previously described. As a result of this resetting, the relay opens its contacts 2UR1 and recloses its break contacts 2UR2 (Fig. 3). Inasmuch as the contacts 5CR2 remain open, the reclosure of the contacts 2UR2 has no immediate effect on the system. However, the relay also recloses its break contacts 2UR3. If no other call is registered affecting the elevator car B, the reclosure of the contacts 2UR3 results in energization of the call relay B78.

Next it will be assumed that a prospective passenger at the fourth floor registers a down floor call by operation of the push button 4D (Fig. 2) after the elevator car A reached the fifth floor. The resultant energization of the down floor registering relay 4DR closes the make contacts 4DR1 to establish a holding circuit around the push button. In addition, the registering relay opens its break contacts 4DR2 (Fig. 3) and similar contacts for the remaining cars, such as the contacts 4DR3 for the elevator car B. The opening of the break contacts 4DR2 deenergizes the call relay 78. This relay recloses its

break contacts 78-1. The down floor registering relay 4DR further closes its make contacts 4DR4 to energize partially the relays 2CC to 5CC, but these relays do not pick up. Opening of break contacts 4DR6 (Fig. 4) starts a timing out operation of the relay 4DRT. It will be assumed that the elevator car A has remained at the fifth floor for time sufficient to permit reclosure of the break contacts 70T1 of the non-interference relay. Consequently, the up switch U and the running relay M are energized in the manner previously described to move the car upwardly to the upper terminal floor. As the elevator car A nears the upper terminal floor, the mechanical switch 28 closes and the brush *ee* (Fig. 2) engages the segment *e6* to complete the following energizing circuit:

L1, *e6*, *ee*, W5, MHCR3, S, EM1 and 28 in parallel, L2

The relay S closes its make contacts S1 (Fig. 1) to energize the relays G, E and F. These relays initiate a stopping operation of the elevator car A at the sixth floor in a manner which will be clear from the earlier discussion of the stopping of the elevator car at the fifth floor. As it reaches the sixth floor, the elevator car A opens its limit switch 23 (Fig. 1) to deenergize the up preference relay W. Since this relay closes its break contacts W2 and the break contacts U6 close as the car stops, an energizing circuit is completed for the down preference relay X through the limit switch 24. The deenergization of the up preference relay and the energization of the down preference relay condition the elevator car A for down travel.

After the expiration of time sufficient to permit the non-interference relay 70T to time out, the break contacts 70T1 close to complete the following circuit:

L1, 70T1, 78-1, X1, F2, 22, D, M, DR1, L2

The relay D upon energization closes its make contact D1 to release the elevator brake. Contacts D2 and D3 close to energize the generator field with proper polarity for down travel. Contacts D4 close to complete through the limit switch 20 and the contacts E2, an energizing circuit for the speed relay V. This relay closes its make contacts V1 to shunt the resistor R1. The elevator car A now accelerates to its full speed in the down direction.

Closure of the make contacts D5 establishes a holding circuit around the contacts 70T1, 78-1, and X1. Opening of the break contacts D6 has no immediate effect on the operation of the system. The running relay M upon energization operates its contacts in the manner previously described.

As the elevator car A nears the fourth floor, the brush *gg* engages the contact segment *g4* (Fig. 2) to complete the following energizing circuit:

L1, 4DR1, *g4*, *gg*, HCR3, X6, S, EM1, L2

As a result of its energization, the floor call stopping relay S closes its make contact to energize the relays G, E and F. The relay G closes its make contact to establish a holding circuit around the contacts S1. The continued movement of the elevator car A brings the inductor slow down relay adjacent the plate DEP for the fourth floor and completes a magnetic circuit resulting in opening of the contacts E2. Such opening results in deenergization of the speed relay V and this relay closes its contacts V2 (Fig. 2) and opens it makes contact V1 (Fig. 1) to introduce the resistor R1 in series with the generator field winding. The decrease in energization of the field winding slows the elevator car to a landing speed. The continued movement of the elevator car A at a slow speed brings the inductor stopping relay F adjacent the inductor plate DFP to open the contacts F2. Such opening deenergizes the down switch D and the running relay M. The down switch D opens its make contacts D1 to apply the elevator brake. Contacts D2 and D3 open to deenergize the generator field winding and the elevator car

75

stops accurately at the fourth floor. Opening of make contacts D4 and D5 and closure of break contacts D6 have no immediate effect on the operation of the system.

During the stopping operation the brush hh (Fig. 2) engages the contact segment h4 to complete the following cancelling circuit:

L1, 4DR1, 4DRN, h4, hh, X7, V2, L2

In resetting, the relay 4DR opens its holding contacts 4DR1. In addition, the relay recloses its break contact 4DR2 (Fig. 3) and corresponding contacts in the call circuits for the remaining elevator cars of the bank. If no other call is registered affecting the call circuit 30, the call relay 78 is energized and prevents further operation of the elevator car A. Opening of contacts 4DR4 interrupts the partial energization of the relays 2cc to 5cc. Contacts 4DR6 (Fig. 4) are assumed to reclose before the relay 4DR has timed out.

It will be assumed that the passenger at the fourth floor enters the elevator car and operates the push button 1c (Fig. 2) to initiate movement of the elevator car to the first floor. The resultant energization of the car call registering relay 1CR closes the holding contacts 1CR1 and opens the break contacts 1CR2 (Fig. 3). Opening of the contacts 1CR2 deenergizes the call relay 78 and this relay closes its break contacts 78-1 (Fig. 1) to permit further movement of the elevator car. If sufficient time has elapsed for the non-interference relay 70T to drop out, the break contacts 70T1 close. If the doors also are closed, an energizing circuit again is completed for the down switch D and the running relay M. These cooperate in the manner previously discussed to move the elevator towards the first floor.

Closure of contacts 1CR3 partially energizes the relays MHCR and HCR.

As the elevator car A nears the first floor, the brush aa (Fig. 2) engages the contact segment a1 to complete an energizing circuit for the car call stopping relay T. This relay closes its make contacts T1 to energize the relays G, E and F through the contacts M1. The energized relays E and F cooperate in the manner previously described to stop the elevator car A at the first floor. As the elevator car stops, the brush dd engages the contact segment d1 to complete the following cancelling circuit:

L1, 1CR1, 1CRN, d1, dd, W4, M5, L2

In resetting, the relay 1CR opens its holding contacts 1CR1, and closes its break contacts 1CR2 (Fig. 3) to complete an energizing circuit for the call relay 78. Opening of contacts 1CR3 interrupts the partial energization of relays MHCR and HCR. The relay 78 opens its break contacts 78-1 (Fig. 1) to prevent further operation of the elevator car A until a call is registered requiring such operation.

As it reaches the lower terminal floor, the elevator car A opens the limit switch 24 to deenergize the down preference relay. This relay closes its break contacts X2 to complete an energizing circuit for the up preference relay W as the elevator car stops at the lower terminal floor. The deenergization of the down preference relay X and the energization of the up preference relay W conditions the elevator car A for up travel.

Up-peak operation

It now will be assumed that all of the elevator cars are parked at the lower terminal floor when a passenger entering the elevator car A registers a car call for the second floor and passengers register car calls in the elevator car B for the third, fourth and fifth floors. It is assumed that the switches SW2 and SW4 are open and that the switch SW3 (Fig. 3) connects the relay MHCR in series with the relay HCR. Such registrations result in opening of the break contacts 2CR2, B3CR2, B4CR2 and B5CR2 (Fig. 3) and relays 78 and B78 drop out. In addition, make contacts 2CR3, B3CR3, B4CR3 and B5CR3 (not

shown in Fig. 4) close to energize the car call quota relays MHCR and HCR. It is assumed in this example that the resistors R8, etc. are so dimensioned that currents flowing through at least three resistors are required to energize the quota relay MHCR sufficiently to pick up, and that currents flowing through at least six resistors are required to pick up the quota relay HCR.

The registration of a large number of car calls indicates the presence of a substantially high service demand. Inasmuch as each stop of the elevator car requires substantial time, it follows that the stopping of the elevator cars a number of times as required by a large number of registered car calls appreciably slows the elevator cars.

The registration of a large number of car calls at the lower terminal floor may occur, for example, during an up peak period such as the start of a business day in an office building served by the elevator system. For this reason, it is desirable to expedite the return of the elevator car to the lower terminal floor.

If desired, the return of the elevator car further may be expedited by preventing the elevator car A from answering certain registered floor calls during its travel. For example, during the morning up peak, few up calls generally are registered by operations of the up floor call push buttons. For this reason, it is permissible in many cases to expedite the return of the elevator cars to the lower terminal floor by preventing one or more of the elevator cars from answering registered up floor calls during up travel thereof. To this end, the break contacts 25 MHCR3 (Fig. 2) of the first quota relay MHCR open when this relay is energized to prevent energization of the floor call stopping relay during up travel of the elevator car A. Similar contacts may be employed in other cars if so desired. However, as shown, they are not provided for the elevator car B.

To expedite return of the elevator car A, it is desirable that the break contacts of the floor call relays in the call circuit 30 be shunted during such travel of the elevator car. To this end, the make contacts MHCR4 to MHCR8 of the quota relay MHCR shunt the break contacts of the floor call relays above the first floor in the call circuit 30. As shown, such contacts are not provided for the elevator car B.

The elevator car A proceeds upwardly in the manner previously described answering the registered car call for the second floor. As the elevator car nears the second floor, the brush kk (Fig. 3) engages the contact segment k2 to complete the following energizing circuit for the call-above relay 78U:

L1, 6CR2, MHCR4, 5CR2, MHCR5, 4CR2, MHCR6, 3CR2, MHCR7, k2, kk, W7, 78U, L2

As a result of its energization, the call-above relay closes its make contacts 78U1 (Fig. 1) to complete with the contacts MHCR1 and X3 an energizing circuit for the reversal relay J which closes contacts J1 to energize the relays G, E and F. Under the assumed conditions, these relays G, E and F also would have been energized in the manner previously described as the elevator car A answered the registered car call for the second floor.

In addition, the reversal relay opens its break contact J2. Inasmuch as the make contacts M2 of the running relay open as the car comes to a stop, it follows that the up preference relay W is deenergized as the elevator car stops at the fourth floor. The deenergized up preference relay closes its break contacts W2 to complete an energizing circuit for the relay X. Since the down preference relay now is energized and the up preference relay W is deenergized the elevator car A is conditioned to return to the lower terminal floor. The operation of the system in returning the elevator car A to the lower terminal floor will be understood from the foregoing discussion. By reversing the elevator car A at the intermediate floor, the return of the elevator car to the lower terminal floor is materially expedited.

To assure prompt return of the elevator car A to the first floor, the manual switch 31 may be closed to connect the mechanical switch 32 across the push button 1c for the first floor. This mechanical switch is biased into closed condition and is cam-operated to open as the elevator car A reaches the lower terminal floor. Consequently, as soon as the car leaves the first floor the switch 32 closes to establish a parking call for the first floor.

Let it be assumed next that before the elevator car A left the first floor two additional car calls were registered by passengers therein pressing the buttons 5c and 6c. This results in the energization of the relays HCR and MHCR (Fig. 3) through the make contacts 5CR3 and 6CR3 as well as through the make contacts 2CR3, B3CR3, B4CR3 and B5CR3. Both relays HCR and MHCR are picked up under these conditions. The effect of pickup of the relay MHCR has been discussed.

Upon picking up, the relay HCR opens its break contacts HCR1 and HCR2 (Fig. 2) to prevent response of the elevator car B to all floor calls. Opening of contacts HCR3 prevents response by the elevator car A to down floor calls.

Closure of contacts HCR4 to HCR8 (Fig. 3) shunts the contacts of the floor call registering relays for floors above the first floor. Consequently the elevator car B is conditioned to reverse when it reaches the farthest floor in the up direction for which a car call is registered.

The effect of closure of the switches SW2 and SW4 and of operation of the switch SW3 to its upper position, as viewed in Fig. 4, on the operation of the system now will be considered. When the switch SW3 is in its upper position, a shunt is connected across the poles or blades of the switch.

It again will be assumed that a passenger entering the elevator car A registers a car call for the second floor, and passengers register car calls in the elevator car B for the third, fourth and fifth floors. It will be assumed first that these passengers enter the elevator cars at a time when a balanced demand for elevator service is anticipated. Consequently, contacts CL4 of the time switch are closed and contacts CL5 of the time switch are open.

When the switch SW2 was closed, the first timing relay PUT was energized through the contacts 2CC3, IT3 and PU1. Consequently, break contacts PUT1 are now open. As a result of the energization of the relay PU through the make contacts 2CR3, B3CR3, B4CR3 and B5CR3 (not shown in Fig. 4), the relay PU picks up to open its break contacts PU1 and close its make contacts PU2. Opening of the break contacts PU1 starts a timing out operation of the first timing relay PUT. Inasmuch as an intense demand for up service is not anticipated at this time, the contacts CL4 are closed and the relay PUT has a long time delay in dropout. As a specific example, this time delay may be of the order of 5 seconds. The closure of the make contacts PU2 completes with the break contacts 2CC3 and IT3 and the switch SW2 an energizing circuit for the second timing relay DOT which closes its make contacts DOT1 without immediate effect on the operation of the system.

Upon the expiration of its time delay, the relay PUT drops out to close its break contacts PUT1. This completes with the break contacts 2CC3 and IT3 an energizing circuit for the first car call quota relay MHCR, which operates in the manner previously described to expedite elevator service in the up direction. However, because of the operation of the relay PUT, the conditions necessary to cause energization of the relay MHCR must persist for at least 5 seconds. In addition, the relay MHCR closes its make contacts MHCR9 to complete with the contacts DOT1 a holding circuit around the break contacts PUT1.

When a sufficient number of car calls have been answered, the relay PU drops out to close its break contacts PU1 which results in energization of the first timing relay PUT. The resultant opening of the break contacts PUT1 has no immediate effect on the operation of the system.

In addition, the make contacts PU2 open to deenergize the second timing relay DOT. Inasmuch as the contacts CL5 of the time switch are open, the relay DOT has a short or negligible time delay in dropout which may be of the order of three seconds. Upon the expiration of this time delay, the relay DOT drops out to open its make contacts DOT1 and deenergize the relay MHCR. The effect of the deenergization of the relay MHCR has been discussed previously.

- 10 From the foregoing discussion, it is clear that if a number of car calls are registered at a time when no intense demand for up service is anticipated, the transfer of the system to up-peak operation is delayed, and the return of the elevator system to balanced operation is expedited.
- 15 Let it be assumed next that the aforesaid passengers registered their calls at a time when an intense demand for service in the up direction was to be anticipated. Such a time may, for example, be between 7:30 A. M. and 8:00 A. M. During this period, the time switch opens its make contacts CL4 and closes its contacts CL5. This means that the time delay in dropout of the relay PUT is negligible, whereas the time delay in dropout of the relay DOT is substantial, such as a time delay of two minutes. Under these circumstances, pickup of the relay PU 25 promptly transfers the system to up-peak operation, and when the relay PU drops out, the return of the elevator system to off-peak operation is subjected to the full delay of 2 minutes introduced by the relay DOT. Consequently, the system tends to maintain its up-peak service despite 30 momentary decreases in the number of registered car calls.

Relays similar to the relays PU, PUT and DOT may be employed in a similar manner for controlling the energization and dropout of the relay HCR.

Down peak operation

- 35 For the purpose of illustrating the gradual increase in carrying capacity in the system in the down direction as the demand for elevator service increases, it will be assumed initially that down floor calls are registered at the second and third floors. The sequence for registering such calls will be understood from the foregoing discussion. It will be recalled that as a result of registration of these floor calls the break contacts 2DR5 and 3DR6 (Fig. 4) open and the floor call timing relays 2DRT and 3DRT start to time out.
- 40 In addition the down call quota relays 2CC, 3CC, 4CC and 5CC all are energized through two arms of the associated parallel circuit. Such energization is sufficient to pick up only the relay 2CC. For present purposes the switch SW1 is open and the switch SW6 connects the relay 2CC in series with the relays 3CC to 5CC.
- 45 As a result of its energization the down call quota relay 2CC closes its make contacts 2CC1 (Fig. 1) to prepare the reversal relay J for subsequent energization. Similar contacts 2CC2 associated with the reversal relay BJ for the elevator car B also are enclosed. Each of the elevator cars now is conditioned during up travel to stop and reverse at the highest floor for which a call is registered provided such call is not an up floor call. For example, 50 let it be assumed that immediately after the pick up of the down call quota relay 2CC the elevator car A is traveling up and approaches the third floor. During such approach the brush kk (Fig. 3) engages the contact segment k3. Since it is assumed that no call is registered for a floor above the third floor and that no up floor call is registered for the third floor, the following circuit is completed:
- 55 L1, 6CR2, 6DR2, 5UR2, 5CR2, 5DR2, 4UR2, 4CR2, 4DR2, 3UR2, k3, kk, W7, 78U, L2
- 60 Since the call above relay 78U now is energized, the make contact 78U1 (Fig. 1) closes to complete with the contacts 2CC1 and X3 an energizing circuit for the reversing relay J. This energized relay then operates in the manner previously discussed to stop and reverse the elevator car A at the third floor. During its return to the 65

lower terminal floor, the elevator car A accepts passengers from the third and second floors in a manner which will be understood from the preceding discussion.

When it picks up, the down call quota relay 2CC also opens its break contacts 2CC3 to prevent energization of the car call quota relays MHCR and HCR.

Next it will be assumed that a down floor call is registered only for the second floor but that this floor call has remained unanswered for a time sufficient to permit dropout of the floor call timing relay 2DRT (Fig. 4). It will be recalled that this timing relay starts to time out as soon as registration of a call at the second floor opens the break contacts 2DR5.

Upon dropping out the floor call timing relay 2DRT closes its break contacts 2DRT1 (Fig. 3) to energize the timed call relays 1T to 4T. However, the energization of these relays through only one arm of the associated parallel circuit is sufficient to pick up only the relay 1T.

Upon pickup the relay 1T closes its make contacts 1T1 and 1T2 (Fig. 1) to prepare the reversal relays for subsequent energization. Consequently, the effect of the closure of the contacts 1T1 and 1T2 is similar to that of the closure of the contacts 2CC1 and 2CC2 which has just been described.

In addition the timed call relay 1T opens its break contacts 1T3 (Fig. 3) to prevent energization of the car call quota relays HCR and MHCR.

From the foregoing discussion it is clear that the pickup of either the relay 2CC or the relay 1T results in an increase in the carrying capacity of the elevator system in the down direction.

Next it will be assumed that down floor calls are registered for the second, third and fourth floors. As a result of such registrations, the break contacts 2DR5, 3DR6 and 4DR6 (Fig. 4) open to start timing out operations of the floor call timing relays 2DRT, 3DRT and 4DRT.

The registration of these three calls also results in closure of the make contacts 2DR4, 3DR4 and 4DR4 (Fig. 3) to energize the down call quota relays 2CC, 3CC, 4CC and 5CC. However, the energization applied through three arms of the parallel circuits is sufficient to pick up only the relays 2CC and 3CC. The relay 2CC operates in the manner previously discussed to condition the elevator cars to reverse when traveling up at the highest floor for which a call is registered unless the call is an up floor call. The relay 3CC opens its break contacts 3CC1 (Fig. 2) to prevent the elevator car B from responding to up floor calls. Also contacts 3CC2 close to energize the relay USE. The relay USE closes its contacts USE1 to USE4 for the purpose of shunting contacts of the up floor-call registering relays in the circuit B30 for the elevator car B. The elevator car B now is set to reverse at the highest of the car calls and down floor calls. This further expedites elevator service in the down direction.

Next let it be assumed that two down floor calls are registered for the second and third floors and that these calls have been registered for a time sufficient to permit dropout of the floor call timing relays 2DRT and 3DRT (Fig. 4). As a result of such dropouts these relays close their break contacts 2DRT1 and 3DRT1 (Fig. 4) to energize the timed call relays 1T to 4T. However, such energization through two of the parallel arms associated with the relays suffices to pick up only the relays 1T and 2T. The relay 1T operates in the manner previously described to condition the elevator cars to reverse when traveling up at the highest floor for which a call is registered provided such call is not an up floor call. The relay 2T opens its break contacts 2T1 (Fig. 2) to prevent the elevator car B from responding to up floor calls. In this way service in the down direction is expedited.

For the next operation to be discussed it will be assumed that down floor calls are registered for the second, third, fourth and fifth floors. As a result of such registrations

make contacts 2DR4, 3D4R, 4DR4 and 5DR4 (Fig. 3) close to energize the down call quota relays 2CC, 3CC, 4CC and 5CC through four arms of the associated parallel circuit. Such energization suffices to pick up the relays 2CC, 3CC and 4CC. The operation of the relays 2CC and 3CC has been discussed above.

Upon picking up the down call quota, relay 4CC closes its make contacts 4CC1 to energize the first down service demand relay DSE. This relay further expedites travel in the desired direction as by dividing the floors into groups or zones and assigning a separate car or group of cars to each zone of floors. Such zoning during down peak periods is well known in the art.

Had only three down floor calls been registered and had all of the three calls timed out, the timed call relays 1T to 4T (Fig. 3) would have been energized through three arms of the parallel circuit. Such energization would have sufficed to pick up the relays 1T, 2T and 3T. The relays 1T and 2T would operate in the manner previously described. The pickup of the relay 3T would result in closure of the make contacts 3T1 to energize the first down service demand relay. Consequently, the energization of either of the relays 3T or 4CC results in a substantial increase in the carrying capacity of the elevator system in the down direction.

For the next condition to be examined it will be assumed that down floor calls are registered for the second, third, fourth, fifth and sixth floors. Under such circumstances the down call quota relays 2CC to 5CC will be energized through all of the parallel arms associated therewith and all of the quota relays will be picked up. Inasmuch as the effect of pickups of the relays 2CC, 3CC and 4CC already has been considered, consideration need be given at this point only to the effect of the pickup of the quota relay 5CC.

As a result of its pickup, the quota relay 5CC closes its make contacts 5CC1 to energize the second down service demand relay EM. It should be noted that this relay also may be energized as a result of closure of the make contacts 4T1. Consequently, a similar result is obtained if four down floor calls have been registered for a time sufficient to permit dropout of four of the floor call timing relays 2DRT to 6DRT. Under such circumstances the timed call relays 1T to 4T (Fig. 4) would be energized through four arms of the associated parallel circuit and all of the timed call relays would be picked up. As before noted, the pickup of the relay 4T results in closure of the make contacts 4T1 to energize the second down service demand relay EM.

Pickup of the second down service demand EM results in opening of the break contacts EM1 and EM2 to prevent energization of the floor call stopping relays S and BS. The stopping of the elevator cars during down travel now is controlled by the timed floor call stopping relays SE and BSE (Fig. 4). An elevator car now stops in response to a down floor call only if the down floor call has been registered for more than a predetermined time. Inasmuch as passengers tend to accumulate during the time required to make a down floor call effective for stopping the elevator car, it follows each stop of an elevator car in response to such a call results in the loading of a larger number of passengers and an increase in the capacity of the elevator system to carry passengers in the down direction.

To illustrate the stopping operation under these conditions, it will be assumed that the elevator car A is traveling down towards the third floor and that a down floor call for the third floor has been registered for a time sufficient to permit the floor call timing relay 3DRT to time out and close it breaks contacts 3DRT2. As the elevator car A approaches the third floor, the brush *nn* engages the contact segment *n3* to complete the following energizing circuit:

The energized time floor call stopping relay SE now closes its make contacts SE1 to complete with the make contacts M1 an energizing circuit for the relays E, F and G. These cooperate in the manner previously discussed to stop the elevator car A at the third floor.

If either of the relays 5CC or 4T is energized and picked up, it follows that either the relay 2CC or the relay 1T must be picked up to close its contacts 1T1 or 2CC1 (Fig. 1). Consequently, if the elevator system is conditioned during down travel to respond only to down floor calls which have been registered for more than a predetermined time, the contacts 1T1 or 2CC1 must be closed to condition the elevator cars to reverse at the farthest floor when traveling in the up direction for which a call is registered provided such a call is not an up call. Under these conditions, it may be desirable to connect the call above relay 78U to a circuit which energizes the relay as the associated elevator car nears the highest floor for which either a car call is registered or a down floor call has been registered for more than a predetermined time. For present purposes, it will suffice to condition the relay 78U to pick up when the elevator car during up travel nears the highest floor for which a car call or a down floor call is registered. To this end make contacts EM3 to EM6 are associated with the call circuit 30 and make contacts USE1 to USE4 are associated with the call circuit B30 for the purpose of shunting contacts of the up floor call registering relays. Consequently, when the second down service demand relay EM is energized, each elevator car is conditioned during up travel to stop at the highest floor for which a car call or a down floor call is registered and to reverse at such floor.

Let it be assumed next that the switch SW6 is operated to its lower position, as viewed in Fig. 3, wherein a shunt is established across its poles or blades. Switch SW5 is closed to connect the relay 2CC for energization through the break contacts PPUTA1 and the switch SW1. The switch SW1 is closed to energize the third timing relay PPUTA which opens its break contacts PPUTA1. Under these circumstances, let it be assumed that the previously discussed down floor calls are registered at the second and third floors, and this registration occurs at a time when a substantial demand for elevator service in the down direction is not anticipated. The relay PPUTA connected in series with the relay 3CC to 5CC is now energized through two arms of the associated parallel circuit. Such energization is sufficient to pick up this relay and open its break contacts PPUTA1. The third timing relay PPUTA now starts to time out. Under the assumed conditions, the contacts CL2 of the time switch are closed, and the relay PPUTA has a substantial time delay in dropout which may be of the order of five seconds. In addition, make contacts PPUTA2 close to energize the fourth timing relay DOTA. This relay closes its make contacts DOTA1 without immediately affecting the operation of the system.

Upon the expiration of the time delay of the relay PPUTA, the relay drops out to close its break contacts PPUTA1 and this closure completes an energizing circuit for the relay 2CC. This relay operates in the manner previously described.

It will be assumed that the down floor call at the third floor is answered and that the make contacts 3DR4 open. Since the relay PPUTA now is energized through only one arm of the associated parallel circuit, this relay drops out to close its break contacts PPUTA1. The reenergization and pickup of the timing relay PPUTA results in opening of the break contacts PPUTA1. Since these contacts are now shunted by the contacts DOTA1 and 2CC4, the pickup of the relay PPUTA does not affect the immediate operation of the system.

At the same time, the make contacts PPUTA2 open to deenergize the fourth timing relay DOTA, and this relay starts to time out. Inasmuch as the operation here under

consideration occurs at a time when an intense demand for elevator service in the down direction is not anticipated, the contacts CL1 of the time switch are open, and the relay DOTA has a small time delay in dropout which may be of the order of three seconds. Upon the expiration of this time delay, the relay opens its make contacts DOTA1 to deenergize the down call quota relay 2CC. The operation of this relay has been previously described.

From the foregoing discussion, it will be clear that a substantial demand for elevator service in the down direction which occurs when an intense demand for down service is not anticipated must persist for a substantial time before the elevator system will be transferred to a down-peak operation. When once transferred, a reduction in the demand for down service during this period results in a rapid return of the elevator system to balanced operation.

Let it be assumed next that the aforesaid demand for down service which resulted in closure of the make contacts 2DR4 and 3DR4 occurred when an intense demand for down service normally is expected. Such a period may be between 5:00 P. M. and 5:30 P. M. of the day. At such a time, the time switch opens its contacts CL2 and closes its contacts CL1. Consequently, when the relay PPUTA picks up, the third timing relay PPUTA drops out promptly to transfer the elevator system to a down-peak mode of operation. When the relay PPUTA thereafter drops out, the fourth timing relay DOTA drops out with substantial time delay which may be of the order of two minutes before the elevator system can be restored to balanced or off-peak operation. For this reason, a momentary decrease in the number of registered down floor calls during a period when an intense demand for down service is anticipated does not result in the restoration of the system to off-peak or balanced operation.

It will be understood that relays similar to the relays PPUTA, PPUTA and DOTA may be employed in an analogous manner for controlling the energization of any of the relays 3CC to 5CC and 1T to 4T.

As previously pointed out, the sensitivity of a relay employed in transferring the system to another mode of operation may be modified during certain periods. For example, the relay 5CC may have a resistor R24 connected in shunt therewith through contacts CL3 of the time switch and break contacts 5CC2 of the down call quota relay 5CC. The contacts CL3 of the time switch are closed during periods in which an intense demand for down service is not anticipated. The contacts CL3 are open during periods in which an intense demand for elevator service in the down direction is anticipated. Consequently, a larger number of down floor calls must be registered to pick up the relay 5CC during periods in which an intense demand for down service is not anticipated than for periods in which an intense demand for down service is anticipated.

This patent application is in part a continuation of my copending patent application Serial No. 443,618, filed July 15, 1954, which in turn is in part a continuation of my patent application Serial No. 264,036, filed December 29, 1951, now Patent 2,688,383.

Although the invention has been described with reference to certain specific embodiments of the invention, numerous modifications embodying the invention are possible. Consequently, the foregoing discussion and the illustrations are to be construed in an illustrative rather than in a limiting sense.

I claim as my invention:

1. In an elevator system, a structure having a plurality of landings, an elevator car, means mounting the elevator car for movement relative to the structure to serve the landings, and control means for moving the elevator car and stopping the elevator car at predetermined landings, said control means comprising means conditioning the elevator car for a first mode of operation, means conditioning the elevator car for a second mode of operation,

transfer means having a first response to the demand for elevator service for transferring the elevator car from the first mode of operation to the second mode of operation, and time-responsive means for establishing a second response of the transfer means to the demand for elevator service which differs from said first-named response of the transfer means for transferring the elevator system from the first mode of operation to the second mode of operation.

2. In an elevator system, a structure having a plurality of landings, an elevator car, means mounting the elevator car movement relative to the structure to serve the landings, and control means for moving the elevator car and stopping the elevator car at predetermined landings, said control means comprising means conditioning the elevator car for a first mode of operation, transfer means for modifying said mode of operation, and period-determining means cooperating with the transfer means for establishing a first period during which said mode of operation is subjected to a first modification in response to the demand for service, said period-determining means cooperating with the transfer means for establishing a second period during which said mode of operation is subjected to a second modification in response to the demand for elevator service.

3. A system as claimed in claim 2 wherein said first modification comprises a first rate of response to a predetermined change in the demand for elevator service for transferring the elevator car from the first mode of operation to a second mode of operation and wherein the second modification comprises a second rate of response to said predetermined change in the demand for elevator service for transferring the elevator car from the first mode of operation to the second mode of operation.

4. In an elevator system, a structure having a plurality of landings, an elevator car, means mounting the elevator car for movement relative to the structure to serve the landings, and control means for moving the elevator car and stopping the elevator car at predetermined landings, said control means comprising means conditioning the elevator car for a first mode of operation wherein the elevator service in two directions of travel of the elevator car is substantially balanced, transfer means responsive to a predominant demand for elevator service in a first direction for establishing a first modification of the mode of operation of the elevator car to provide a second mode of operation of the elevator car wherein elevator service in said first direction is expedited, and time-responsive means establishing a period wherein said transfer means responds to said predominant demand for establishing a second modification of the mode of operation of the elevator car differing from the first modification to expedite elevator service in said first direction.

5. In an elevator system, a structure having a plurality of landings, an elevator car, means mounting the elevator car for movement relative to the structure to serve the landings, and control means for moving the elevator car and stopping the elevator car at predetermined landings, said control means comprising first call means operable for registering calls for elevator service in a first direction for each of a plurality of said landings at which the elevator car is to stop, second call means operable for registering calls for elevator service in a second direction for each of a plurality of said landings at which the elevator car is to stop, expediting means responsive to the demand for elevator service in said directions for apportioning elevator service by said elevator car between said two directions substantially in accordance with a function of the demand for elevator service in said directions, and time-responsive means for modifying said function.

6. In an elevator system, a structure having a plurality of landings, a plurality of elevator cars, means mounting the elevator cars for movement relative to the struc-

ture to serve the landings, and control means for moving and stopping each of the elevator cars, said control means comprising first call means for registering calls for elevator service in a first direction for each of a plurality of said landings, second call means for registering calls for elevator service in a second direction for each of a plurality of said landings, means for stopping the first available one of the elevator cars which approaches one of the landings for which a call is registered by the call means which may be served by movement in the direction of the approach of such available elevator car, modifying means responsive to a change in the demand for elevator service in the first direction for changing the capacity of the elevator system to answer calls for elevator service in the first direction, and time-responsive means for adjusting the modifying means to provide a different response of said modifying means to a change in said demand for elevator service.

7. In an elevator system, a structure having a plurality of landings, a plurality of elevator cars, means mounting the elevator cars for movement relative to the structure to serve the landings, and control means for moving and stopping each of the elevator cars, said control means comprising first call means for registering calls for elevator service in a first direction for each of a plurality of said landings, second call means for registering calls for elevator service in a second direction for each of a plurality of said landings, means for stopping the first available one of the elevator cars which approaches one of the landings for which a call is registered by the call means which may be served by movement in the direction of the approach of such available elevator car, modifying means responsive with time delay to a predetermined condition for modifying the operation of the elevator cars, and time-responsive means for altering the value of said time delay during a predetermined period of time.

8. In an elevator system, a structure having a plurality of landings, a plurality of elevator cars, means mounting the elevator cars for movement relative to the structure to serve the landings, and control means for moving and stopping each of the elevator cars, said control means comprising first call means for registering calls for elevator service in a first direction for each of a plurality of said landings, second call means for registering calls for elevator service in a second direction for each of a plurality of said landings, means for stopping the first available one of the elevator cars which approaches one of the landings for which a call is registered by the call means which may be served by movement in the direction of the approach of such available elevator car, modifying means responsive to a predetermined increase in the demand for elevator service in the first direction for augmenting the capacity of the elevator system to answer calls for elevator service in said first direction, means responsive to a predetermined decrease in the demand for elevator service in the first direction while the system is conditioned to provide said augmented capacity for decreasing with time delay said capacity, and time-responsive means for modifying the value of said time delay.

9. A system as claimed in claim 8 wherein said time-responsive means includes means effective during a predetermined period of time for altering the value of said predetermined increase to which the modifying means responds.

10. In an elevator system, a structure having a plurality of landings, a plurality of elevator cars, means mounting the elevator cars for movement relative to the structure to serve the landings, and control means for moving and stopping each of the elevator cars, said control means comprising first call means for registering calls for elevator service in a first direction for each of a plurality of said landings, second call means for registering calls for elevator service in a second direction for each of a plurality of said landings, means for stopping the

first available one of the elevator cars which approaches one of the landings for which a call is registered by the call means which may be served by movement in the direction of the approach of such available elevator car, modifying mean responsive to a predetermined increase in the demand for elevator service in the first direction for augmenting the capacity of the elevator system to answer calls for elevator service in said first direction, and time-responsive means for changing the value of said predetermined increase to which the modifying means responds.

11. In an elevator system, a structure having a plurality of landings including a first terminal landing, a second terminal landing and a plurality of intermediate landings positioned between the terminal landings, an elevator car, means mounting the elevator car for movement relative to the structure to serve the landings, and control means for moving the elevator car and stopping the elevator car at predetermined landings, said control means comprising first call means operable for registering calls for elevator service in a first direction for each of a plurality of said landings at which the elevator car is to stop, second call means operable for registering calls for elevator service in a second direction for each of a plurality of the landings at which the elevator car is to stop, said control means having a first condition wherein the elevator car moves from one to the other of the terminal landings and stops during each trip at each landing approached by the elevator car for which a call is registered by the call means for the direction of travel of the approaching elevator car, said control means having a second condition wherein the elevator car moves on trips from the first terminal landing towards the second terminal landing and wherein the elevator car during travel towards the second terminal landing stops and reverses at an intermediate one of the landings under circumstances such that no call is registered by the call means which can be answered only by further travel of the elevator car towards the second terminal landing, transfer means operating in response to a traffic condition for transferring the control means from one to the other of said first and second conditions, and time-responsive means effective during a predetermined period of time for modifying the conditions under which the transfer means responds to the traffic condition for effecting said transferring of the control means.

12. In an elevator system, a structure having a plurality of landings including a first terminal landing, a second terminal landing and a plurality of intermediate landings positioned between the terminal landings, an elevator car, means mounting the elevator car for movement relative to the structure to serve the landings, and control means for moving the elevator car and stopping the elevator car at predetermined landings, said control means comprising first call means operable for registering calls for elevator service in a first direction for each of a plurality of said landings at which the elevator car is to stop, second call means operable for registering calls for elevator service in a second direction for each of a plurality of the landings at which the elevator car is to stop, said control means having a first condition wherein the elevator car moves from one to the other of the terminal landings and stops during each trip at each landing approached by the elevator car for which a call is registered by the call means for the direction of travel of the approaching elevator car, said control means having a second condition wherein the elevator car moves on trips from the first terminal landing towards the second terminal landing and wherein the elevator car during travel towards the second terminal landing stops and reverses at an intermediate one of the landings under circumstances such that no call is registered by the call means which can be answered only by further travel of the elevator car towards the second terminal landing,

transfer means operating in response to a predetermined traffic condition for transferring the control means from one to the other of said first and second conditions, and time-responsive means effective during a predetermined period of time for modifying the delay with which the transfer means responds to said traffic conditions.

13. In an elevator system, a structure having a plurality of landings including a first terminal landing, a second terminal landing and a plurality of intermediate landings positioned between the terminal landings, an elevator car, means mounting the elevator car for movement relative to the structure to serve the landings, and control means for moving the elevator car and stopping the elevator car at predetermined landings, said control means comprising first call means operable for registering calls for elevator service in a first direction for each of a plurality of said landings at which the elevator car is to stop, second call means operable for registering calls for elevator service in a second direction for each of a plurality of the landings at which the elevator car is to stop, said control means having a first condition wherein the elevator car moves from one to the other of the terminal landings and stops during each trip at each landing approached by the elevator car for which a call is registered by the call means for the direction of travel of the approaching elevator car, said control means having a second condition wherein the elevator car moves on trips from the first terminal landing towards the second terminal landing and wherein the elevator car during travel towards the second terminal landing stops and reverses at an intermediate one of the landings under circumstances such that no call is registered by the call means which can be answered only by further travel of the elevator car towards the second terminal landing, transfer means operating in response to a predetermined traffic condition for transferring the control means from one to the other of said first and second conditions, and time-responsive means effective during a predetermined period of time for modifying the value of the traffic condition in response to which the transfer means operates.

14. In an elevator system, a structure having a plurality of landings including a first terminal landing, a second terminal landing and a plurality of intermediate landings positioned between the terminal landings, an elevator car, means mounting the elevator car for movement relative to the structure to serve the landings, and control means for moving the elevator car and stopping the elevator car at predetermined landings, said control means comprising first call means operable for registering calls for elevator service in a first direction for each of a plurality of said landings at which the elevator car is to stop, second call means operable for registering calls for elevator service in a second direction for each of a plurality of the landings at which the elevator car is to stop, said control means having a first condition wherein the elevator car moves from one to the other of the terminal landings and stops during each trip at each landing approached by the elevator car for which a call is registered by the call means for the direction of travel of the approaching elevator car, said control means having a second condition wherein the elevator car moves on trips from the first terminal landing towards the second terminal landing and wherein the elevator car during travel towards the second terminal landing stops and reverses at an intermediate one of the landings under circumstances such that no call is registered by the call means which can be answered only by further travel of the elevator car towards the second terminal landing, transfer means operating in response to a traffic condition for transferring the control means from an initial one to the other of said first and second conditions, said transfer means being responsive to a predetermined change in the traffic condition for restoring the control means to

said initial one of the conditions, and time-responsive means for modifying the response of the transfer means to said traffic conditions during predetermined spaced periods of time.

15. In an elevator system, a structure having a plurality of landings including a first terminal landing, a second terminal landing and a plurality of intermediate landings positioned between the terminal landings, an elevator car, means mounting the elevator car for movement relative to the structure to serve the landings, and control means for moving the elevator car and stopping the elevator car at predetermined landings, said control means comprising first call means operable for registering calls for elevator service in a first direction for each of a plurality of said landings at which the elevator car is to stop, second call means operable for registering calls for elevator service in a second direction for each of a plurality of the landings at which the elevator car is to stop, said control means having a first condition wherein the elevator car moves from one to the other of the terminal landings and stops during each trip at each landing approached by the elevator car for which a call is registered by the call means for the direction of travel of the approaching elevator car, said control means having a second condition wherein the elevator car moves on trips from the first terminal landing towards the second terminal landing and wherein the elevator car during travel towards the second terminal landing stops and reverses at an intermediate one of the landings under circumstances such that no call is registered by the call means which can be answered only by further travel of the elevator car towards the second terminal landing, transfer means operating in response to a traffic condition for transferring the control means from an initial one to the other of said first and second conditions, said transfer means being responsive to a predetermined change in the traffic condition for restoring the control means to said initial one of the conditions, and time-responsive means for modifying the delay in response of the transfer means to said traffic condition during predetermined spaced periods of time.

16. In an elevator system, a structure having a plurality of landings including a first terminal landing, a second terminal landing and a plurality of intermediate landings positioned between the terminal landings, an elevator car, means mounting the elevator car for movement relative to the structure to serve the landings, and control means for moving the elevator car and stopping the elevator car at predetermined landings, said control means comprising first call means operable for registering calls for elevator service in a first direction for each of a plurality of said landings at which the elevator car is to stop, second call means operable for registering calls for elevator service in a second direction for each of a plurality of the landings at which the elevator car is to stop, said control means having a first condition wherein the elevator car moves from one to the other of the terminal landings and stops during each trip at each landing approached by the elevator car for which a call is registered by the call means for the direction of travel of the approaching elevator car, said control means having a second condition wherein the elevator car during travel towards the second terminal landing stops and reverses at an intermediate one of the landings under circumstances such that no call is registered by the call means which can be answered only by further travel of the elevator car towards the second terminal landing, transfer means operating in response to a traffic condition for transferring the control means from an initial one to the other of said first and second conditions, said transfer means being responsive to a predetermined change in the traffic condition for restoring the control means to said initial one of the conditions, and time-responsive means for modifying the magnitude of said traffic condition to which the transfer means responds

75

during spaced periods of time, said traffic condition being a service demand.

17. In an elevator system, a structure having a plurality of landings including a first terminal landing, a second terminal landing and a plurality of intermediate landings positioned between the terminal landings, a plurality of elevator cars, means mounting the elevator cars for movement relative to the structure to serve the landings, and control means for moving the elevator cars and stopping the elevator cars at predetermined landings, said control means comprising first call means operable for registering calls for elevator service in a first direction for each of a plurality of said landings at which one of the elevator cars is to stop, second call means operable for registering calls for elevator service in a second direction for each of a plurality of the landings at which one of the elevator cars is to stop, said control means having a first condition wherein each of the elevator cars moves from one to the other of the terminal landings and stops during each trip at each landing approached by the elevator car for which a call is registered by the call means for the direction of travel of the approaching elevator car, said control means having a second condition wherein each of the elevator cars moves on trips from the first terminal landing towards the second terminal landing and wherein each of the elevator cars during travel towards the second terminal landing stops and reverses at an intermediate one of the landings under circumstances such that no call is registered by the call means which can be answered only by further travel of the elevator-car-to-be-reversed towards the second terminal landing, transfer means operating in response to a traffic condition for transferring the control means from one to the other of said first and second conditions, and time-responsive means effective during a predetermined period of time for modifying the conditions under which the transfer means responds to the traffic condition for effecting said transferring of the control means.

18. In an elevator system, a structure having a plurality of landings including a first terminal landing, a second terminal landing and a plurality of intermediate landings positioned between the terminal landings, a plurality of elevator cars, means mounting the elevator cars for movement relative to the structure to serve the landings, and control means for moving the elevator cars and stopping the elevator cars at predetermined landings, said control means comprising first call means operable for registering calls for elevator service in a first direction for each of a plurality of said landings at which one of the elevator cars is to stop, second call means operable for registering calls for elevator service in a second direction for each of a plurality of the landings at which one of the elevator cars is to stop, said control means having a first condition wherein each of the elevator cars moves from one to the other of the terminal landings and stops during each trip at each landing approached by the elevator car for which a call is registered by the call means for the direction of travel of the approaching elevator car, said control means having a second condition wherein each of the elevator cars moves on trips from the first terminal landing towards the second terminal landing and wherein each of the elevator cars during travel towards the second terminal landing stops and reverses at an intermediate one of the landings under circumstances such that no call is registered by the call means which can be answered only by further travel of the elevator car to be reversed towards the second terminal landing, transfer means operating in response to a traffic condition for transferring the control means from one to the other of said first and second conditions, and time-responsive means effective during a predetermined period of time for modifying the delay in response of the transfer means to the traffic condition for effecting said transferring of the control means.

19. In an elevator system, a structure having a plu-

rality of landings including a first terminal landing, a second terminal landing and a plurality of intermediate landings positioned between the terminal landings, a plurality of elevator cars, means mounting the elevator cars for movement relative to the structure to serve the landings, and control means for moving the elevator cars and stopping the elevator cars at predetermined landings, said control means comprising first call means operable for registering calls for elevator service in a first direction for each of a plurality of said landings at which one of the elevator cars is to stop, second call means operable for registering calls for elevator service in a second direction for each of a plurality of the landings at which one of the elevator cars is to stop, said control means having a first condition wherein each of the elevator cars moves from one to the other of the terminal landings and stops during each trip at each landing approached by the elevator car for which a call is registered by the call means for the direction of travel of the approaching elevator car, said control means having a second condition wherein each of the elevator cars moves on trips from the first terminal landing towards the second ter-

15 minal landing and wherein each of the elevator cars during travel towards the second terminal landing stops and reverses at an intermediate one of the landings under circumstances such that no call is registered by the call means which can be answered only by further travel of the elevator car to be reversed towards the second terminal landing, transfer means operating in response to a traffic condition for transferring the control means from one to the other of said first and second conditions, and time-responsive means effective during a predetermined period of time for modifying the magnitude of said traffic condition to which the transfer means responds during spaced periods of time, said traffic condition representing a demand for elevator service.
